DESIGN FOR AN ADJUSTABLE SLIPPER

Joseph Albert Lahnstein and Evelyn K. Lahnstein,
New York, N. Y.

Application December 7, 1948, Serial No. 150,022

Term of patent 14 years

(Cl. D7—7)

To all whom it may concern:

Be it known that Joseph Albert Lahnstein and Evelyn K. Lahnstein, both citizens of the United States of America, residing in the city, county, and State of New York, have invented a new, original, and ornamental Design for an Adjustable Slipper, of which the following is a specification, reference being had to the accompanying drawing, forming a part thereof, wherein:

Fig. 1 is a perspective view of the adjustable slipper of our design illustrated in wearing position with some of the features concealed;

Fig. 2 is a perspective view of the slipper of our design shown in Fig. 1 with the slipper unfolded;

Fig. 3 is a side elevation of the slipper of our design shown in Fig. 1 in wearing position with the front tongue in a low position; and

Fig. 4 is a side elevation of the slipper of our design shown in Fig. 1 in wearing position with the front tongue in a high position.

We claim:

The ornamental design for an adjustable slipper, substantially as shown and described.

J. ALBERT LAHNSTEIN.
EVELYN K. LAHNSTEIN.
